A CORPORATION OF NEW YORK.

ELECTRICAL TIME-LIMIT SWITCH.

947,981.

Specification of Letters Patent.

Patented Feb. 1, 1910.

Application filed March 18, 1902. Serial No. 98,762.

To all whom it may concern:

Be it known that I, PHILIP K. STERN, a citizen of the United States, residing in the city of New York, in the county and State 5 of New York, have invented certain new and useful Improvements in Electrical Time-Limit Switches, of which the following is a specification.

My invention in time-limit electrical 10 switches relates to that class of electrical switches having an electromagnetic motor, usually in the form of a solenoid disposed between the bridges of the switch for releasing a catch hook, upon the overload of 15 electrical current carried by the circuit wires and conductors in which the switch is included, whereby suitable projecting springs 20 ars disposed in connection with the bridges of the switch, to throw the same into an open position when the catch has been struck by a plunger or armature of the electromagnetic motor or solenoid aforesaid. In this connection my improvements have relation to a means whereby an overload may be 25 maintained for a desired period of time before the circuit of which the switch forms part, is interrupted.

I am aware that, previous to my invention in automatic time-limit switches, means have 30 been employed in connection with switches of this character for limiting the time of the overload by means of clockwork and analogous devices.

It is the object of my invention to provide 35 a means carried by the switch base, which is more simple and effective in its operation and less liable to err than those of which I am at present aware, or previous to my invention, and particularly less so than that a class employing clockwork to accomplish the same object.

Another object of my invention is to devise a means of the character stated, for limiting the time of the overload for electrical 45 circuits, which may be readily applied to switches of the character known as bridging contact electrical switches.

In carrying out my invention I have illustrated the disposition of my time-limiting 50 devices for two different types of switches in the two sheets of drawings hereto annexed, which form part of this specification, and in which—

Figure 1 is a front elevation of an elec- 55 trical switch of the bridging contact pattern.

showing two solenoid electromagnets with which I accomplish the purpose of my invention, illustrated in section, the section being taken through the two solenoid magnets and cores vertically; Fig. 2 illustrates a similar disposition of the time-limit features, showing the manner in which the two solenoids co-act when one is placed vertically over the other. In this figure I have shown a side elevation of an electrical bridging contact 60 switch of a somewhat narrower and longer pattern than that illustrated in Fig. 1. In the two figures I have shown the manner by which I carry out the details of the same principle employed in the one case on a wide 65 and rather short switch, and in the other a somewhat elongated and narrow type; and Fig. 3 is a detailed view of an index for adjusting the time-limit, and another index for the strength of the current during the 70 interval of time for which the aforesaid index has been set.

In the drawings, similar characters of reference indicate similar parts.

In applying the time-limit principle 80 aforesaid to switches of this character I have considered the adaptation of a retarding medium, such as that of a viscous fluid contained in a closely fitting chamber, in which the solenoid plunger is adapted to 85 move in a manner whereby the fluid will be required to be displaced by the plunger through calibrated apertures permitting only of a predetermined quantity of transfer of the viscous fluid from the cylinder or 90 chamber in which it is confined, to an escaping cylinder in which it is withheld and caught as the plunger is drawn into the solenoid by the magnetic action of the field of force generated by the current as it circulates around the convolutions of the solenoid; and to this end I have preferred the use of such viscous fluid as glycerin, well 95 boiled, so as to eliminate air and moisture from the same, whereby the adhesion of the fluid to the walls of the cylinder or chamber in which it is confined during its resisting force against the solenoid, may be as nearly uniform and constant as possible; and in employing prepared glycerin for the purpose of maintaining the greatest constancy of the solenoid in the manner aforesaid, I have constructed the confining chamber or cylinder, together with the retaining cylinder, in a manner whereby the same will 100 105 110

be practically moisture-proof, so as to avoid any possibility of moisture being absorbed by the glycerin while the switch is in long continued use in damp or steamy atmospheres such as would be encountered when applied to switch-boards or panel boards in dynamo or engine rooms. It is well known that glycerin in its almost chemically pure condition is extremely hygroscopic, and when considerable moisture has been absorbed by the glycerin the value of it as a retarding agent becomes unknown and, unless such precaution is resorted to against the accumulation of moisture, the time-limit features of the switch could not be depended upon.

In carrying my invention into practice I have preferred to describe the same in connection with that type of switch in which the projecting mechanism for throwing the switch bridges into an open position, is in the form of a spring energized plunger A, and since I do not propose to claim this as any part of my invention, an extended description of the same is not deemed necessary, as any means whereby the switch may be thrown into an open position will be readily understood by those who are skilled in the art to which my invention appertains. The manner in which the projecting device is released by the usual solenoid and plunger C' C', is likewise of that character which is familiar to those who have made a study of automatic electrical circuit breakers, and is therefore sufficiently clear in the illustration to require no particular description. My invention therefore will be confined to that part of the circuit-breaking system contained within the solenoid B' and its combination with the solenoid C' and its concomitants. Extending within the solenoid B', is a tubular casing D between the head E of the inner tubular fluid-containing chamber D' and the upper guide M, connected to the solenoid, the upper end of said chamber D', being in engagement with an inner threaded portion E' of such guide, for the purpose of rigidly holding said tube to its bearing in the head E. The upper extremity of the casing D is in fluid-tight relation with the guide M, by means of gaskets and confining rings g, g', adjustably clamped by set screws G' G''. In the upper portion of the fluid-containing chamber D' are a series of small outlets f, f', whereby the glycerin F contained in the fluid chamber D' is allowed to escape, as will be hereinafter more fully explained. At the opposite extremity of the fluid chamber D' are similar openings f'', f''' arranged in valve-tight connection with corresponding openings h, h' formed in the lower upturned inner portion i and i' of the outer casing D. The arrangement of the aforesaid openings h, h' and f'', f''' is

such as to form a sort of stop cock at the lower extremity of the confining chamber D' and outer casing D, whereby upon rotating the outer casing D by the milled head H, communication between the outer casing D and confining chamber D' may be cut off or established after the manner of a valve-tight stop cock. This feature of my invention affords one means of limiting the time in which the glycerin is allowed to circulate between the upper openings f and f', the lower openings aforesaid, and the interior of the confining chamber at its lower end.

Within the confining chamber D' is a core I, closely fitting the walls of the confining chamber D' in a manner so that no glycerin will be permitted to pass between the line of division of the perimeter of the cylindrical surface of the core I, and the internal cylindrical surface of the confining chamber D'. To carry the core I so that its pole I' may be introduced to different distances in the solenoid B', I provide an adjustable rest in the form of a column or spindle J, which passes through a stuffing box j, which is provided with the usual gland packing. Formed in the column or spindle J is a spline k; and a key K', slidably engaged in the spline is secured to the fixed collar K of the casing, which latter is secured by rivets, screws or other mechanical means, to the lower extremity of the fluid-containing chamber D'. Upon shifting the column or spindle J by the milled head or thumb piece L', which is retained by the screw l and engaging shoulders l' and l'', a vertical movement may be imparted to the column or spindle so as to adjust the pole I' of the core in the zone of magnetic influence of the solenoid B'. Thus it will be readily understood how I am enabled to vary the magnetic induction between the solenoid B' and the pole I' of the core I, as well as the circulation of the glycerin F in the confining chamber D', outer casing D, and communicating openings f'', f''', h and h'.

Slidably playing in the integral guide M is a tappet m, adapted to impinge against a pivoted lever N, as the core I is drawn into the solenoid B' by dynamic induction sufficiently to strike the lower extremity of the tappet m, so as to raise the same and effect the movement of the lever N. The purpose of the lever N is to raise the sliding tube O and plunger O' of the solenoid C' so as to bring the pole I'' sufficiently within the magnetic induction of the solenoid C' to enable the said magnetic induction to project the plunger O' with sufficient force against the lever of the catch P of the circuit-breaker, so as to unlock the projecting device in a manner whereby the switch will be thrown into an open position. Thus it will be understood that the solenoid C', together

- with its concomitants, while illustrated in the usual manner for tripping the spring-actuated mechanism of the circuit-breaker, is disposed in a manner whereby my time-
 5 limit solenoid magnet B' and its concomitants are conjointly operating to produce rupture of the circuit of which the switch forms part, when the overload has become of such a character that will induce a sufficient number of lines of magnetic force to raise the core of the solenoid B' against the retarding effect of the glycerin F, in that time for which the retarding effect has been predetermined by the position of an index Q,
 10 15 denoting the number of seconds or minutes allotted for operation.
- It will be understood by a careful study of the conditions that the two solenoidal systems co-act with each other upon a time limit for an overload, while on instantaneous overloads they operate independently. The function of this will be clear when a study of the solenoid C' is resorted to independently of the solenoid B'. As an explanatory example, a so-called short circuit may be considered as an excess of overload over that which the circuit is designed to carry, and under which conditions the switch would simply act as a circuit-breaker operating under the control of the solenoid C'. The plunger O' being previously set to its lowest extremity, or to a position which would be commensurate with the operation of the same by a current circulating around the solenoid C', for a given short circuit expressed in the value of current strength in amperes, will project the plunger O' violently into the magnetic field of the solenoid C' to a sufficient extent to bring the pole I' into contact with the releasing catch as aforesaid, in a manner to release the switch and break the circuit: but in the meantime, due to the retarding effect of the glycerin upon the plunger I, the solenoidal system B' will not have had a sufficient time within which to effect a rupture of the circuit by the performance of its function upon the lever N, and in this sense the switch would operate merely as a circuit-breaker.
 20 On the other hand however, should the overload be insufficient to raise the plunger O' into the magnetic field of force of the solenoid C',—the plunger I being adjusted to operate on a current strength having a smaller value—will be drawn into the magnetic field of the solenoid B', but being retarded by the resisting force due to the confined glycerin F, the circuit-breaking plunger O' will not be sufficiently introduced into its magnetic field aforesaid until the pole I' of the plunger I shall have contacted with the tappet m, in a manner so as to raise the lever N and tube O which carries the plunger O' as aforesaid, and in this sense the two solenoidal systems B' and C' are independent. It will thus be understood by my invention that I am enabled to provide a means whereby a circuit-breaker having a constantly acting retarding means may be adjusted so as to maintain an overload on the circuit which it is designed to protect for a predetermined period, and at the same time instantly rupture the same circuit upon an excessive overload.
- A feature of my invention which I consider important in connection with circuit-breakers, which is a characteristic of the particular manner in which I carry out the principles aforesaid, lies in the re-adjustment of the releasing mechanism to its normal condition after the overload has subsided. In explanation of this feature the movement of the plunger I, must be under the influence of a current of C value, for a time T, and if T has not been sufficient to effect the release of the spring-projecting mechanism before the value of C has fallen the breaker will not be tripped. This feature of my invention involves a principle of considerable value on motor circuits where an excessive overload frequently occurs during the starting up period for short intervals of time, the apparatus which the circuit-breaker is designed to protect being constructed with a sufficient overload factor to operate on overloads of but short duration.
- In Fig. 2, the solenoid B² and its core I² provided for the time limit overload, are located in lower vertical alinement with respect to the solenoid C² and its core O², redesigned for rupturing the circuit on an instantaneous overload, the core I² resting upon a pedestal J¹, the vertical position of which can be regulated by hand adjusting means L', while the vertically movable tappet m' playing in the top of the casing D², has connections with a shifting pin J² for the upper core O², said connections including hand operable means L² for adjusting the vertical position of the latter pedestal relatively to the core O². The inner confining chamber D³ for the glycerin, has the upper and lower series of openings f⁴, f⁵, the latter co-operating with the openings h² of the upturned inner portion D⁴ of the outer casing, in a manner corresponding with that of the similar parts in the construction disclosed in Fig. 1.
- In Fig. 3, Q designates the index for indicating the retarding period of the time limit overload, while the index Q' correspondingly serves for the adjustment providing for the strength of the current, during the interval of time for which the retarding index has been set.
- The operation will be readily comprehended. Upon an excessive overload, the solenoid C² will elevate its core to trip the

latch P', release the motor and operate the switch, such movements being accomplished entirely independent of the solenoid B² and concomitant parts. When the limit of the 5 lower abnormal overload period is reached, the core I² will contact with the tappet m', raise the same and effect the lifting of the core O², into the area of magnetic influence of the solenoid C², so that said core will then 10 instantaneously rise, trip the latch and operate the switch.

Having described my invention so that those skilled in the art to which it appertains could construct, apply and make use 15 of the same, I claim as new and desire to secure by Letters Patent of the United States:—

1. The combination with an electric circuit, of a freely movable member for opening said circuit, actuating means for said member responsive to predetermined current in said circuit and normally so related to said member that said actuating means is unable to move said member, and means responsive to other predetermined current conditions whereby the relative position of said actuating means and said member is varied to enable said actuating means to move the said member.

2. The combination with an electric circuit having an electromagnetic coil, of a freely movable member of magnetic material so related to the coil that normally said member lies beyond the effective magnetic field of said coil when the current has a predetermined value, and means for moving said member into the effective magnetic field of said coil in response to a flow of current having said predetermined value.

3. The combination with an electric circuit having an electromagnetic coil therein, of a freely movable member composed of magnetic material and normally beyond the effective field of said coil when the current 45 therein has a predetermined value, and means including a time limit device for moving said member into the effective field of said coil under certain other current conditions whereby said coil is enabled to actuate 60 said member.

4. The combination with an electric circuit having an electro-magnetic coil therein, of a freely movable armature normally beyond the effective magnetic field of said coil 65 when the current therein has a predetermined value, and means responsive to current of another predetermined value for moving said armature into the effective field of said coil to enable said coil to move said member, said second means including a magnetic coil and a movable member actuated thereby, a fluid containing cylinder for retarding the movement of said latter member, regulating means for varying the flow 35 of fluid, and means for adjusting the posi-

tion of said latter member with respect to its coil.

5. The combination with an electric circuit, of a freely movable member, actuating means for moving said member in response 70 to a predetermined current flowing in said circuit, a support for said movable member, a second member operatively related to said support, and means for moving said second member and said support in response to certain other current conditions to a position enabling said actuating means to move said member under said current conditions.

6. The combination with an electric circuit, of a freely movable member, actuating 80 means for moving said member in response to a predetermined current flowing in said circuit, a support for said member, a second member provided with a time limit device and operatively related to said support, and 85 means for moving said second member and said support in response to certain other current conditions to a position enabling said actuating means to move said member under said current conditions.

7. The combination, twb electromagnetic coils, a free core for one coil, a support for said core, and a core for the other coil having a time limit device and operatively connected to said support to change the relative 95 position of the first core and its coil under certain current conditions in said coils.

8. The combination with an electric circuit, of a movable member, an electromagnetic coil in said circuit and so related to 100 said movable member that said movable member is actuated thereby in response to a predetermined current flowing in said circuit, and means for changing the relative positions of said coil and member under certain other current conditions, to enable said coil to move said member to actuate said movable member in response to current values less than said predetermined amount.

9. The combination with an electric circuit, of a circuit breaker comprising a switch and restraining means therefor, electromagnetically operated devices including a member and means to actuate it to trip said restraining means upon a predetermined overload of current in said circuit, and a second member operatively associated with said first member for bringing it into operative relation to its actuating means under certain other conditions of overload.

10. The combination with an electric circuit, of a circuit breaker comprising a switch and restraining means therefor, an electromagnetic coil and a movable member of magnetic material so related that normally under certain conditions of overload in said circuit the movable member lies beyond the effective magnetic field of said coil while under certain other conditions of overload said member lies within said field,

and means for moving said member into the effective magnetic field of said coil during the first of said conditions of overload.

11. The combination with an electric circuit, of a circuit breaker comprising a switch and restraining means therefor, an electromagnetic device including a movable element arranged to trip said restraining means, and means for moving said movable element into the effective magnetic field of said electromagnet under certain conditions of overload in said circuit.

12. The combination with an electric circuit, of a circuit breaker comprising a switch and restraining means therefor, an electromagnetic coil, a movable member for causing the release of said restraining means, said movable member being normally out of the effective magnetic field of said electromagnet, and means for moving said member into said magnetic field upon a predetermined overload in said circuit.

13. The combination with an electromag-

net and a movable member actuated thereby, of a time limit device therefor comprising a 25 pair of cylinders arranged the one within the other and having a communicating passageway, means for adjusting the size of the passageway, and an adjustable support for said movable member within said cylinders. 30

14. In combination with an electromagnet and a movable member actuated thereby, of a time limit device therefor comprising a pair of cylinders arranged the one within the other, a communicating opening through 35 the inner cylinder, and means actuated by the rotation of the other cylinder to vary the size of said opening.

In testimony whereof, I have signed my name to this specification in the presence of 40 two subscribing witnesses.

PHILIP K. STERN.
